UNITED STATES PATENT OFFICE.

MAURICE KANE, OF AUSTIN, ILLINOIS.

MOWING-MACHINE.

SPECIFICATION forming part of Letters Patent No. 642,524, dated January 30, 1900.

Application filed May 4, 1898. Serial No. 679,712. (No model.)

To all whom it may concern:

Be it known that I, MAURICE KANE, a citizen of the United States, residing at Austin, in the county of Cook and State of Illinois, 5 have invented a new and useful Mowing-Machine, of which the following is a specification.

This invention relates to mowing-machines.

The object of the invention is to provide a means for maintaining alinement between the 10 cutter-bar and its actuating-pitman.

The invention consists, substantially, in the construction, combination, location, and relative arrangement of parts, all as will be more fully hereinafter set forth, as shown in 15 the accompanying drawings, and finally specifically pointed out in the appended claims.

Referring to the accompanying drawings and to the various views and reference-signs appearing thereon, Figure 1 is a plan view of 20 a mowing-machine embodying the principles of my invention and illustrating the operation thereof. Fig. 2 is a detached detail view, partly in section, of the coupling-arm, showing one form of construction embodying the 25 principles of my invention. Fig. 3 is a transverse sectional view of the same on the line 3 3, Fig. 2, looking in the direction of the arrows. Fig. 4 is a similar view on the line 4 4, looking in the direction of the arrows. Fig. 5 is 30 a view similar to Fig. 2, showing a modified form of construction embodying the principles of my invention and wherein is employed an eccentric sleeve. Fig. 6 is a broken detail view in plan of a modified form of coupling-arm, showing the application of the principles of my invention. Fig. 7 is a detail sectional view of the same on the line 7 7, Fig. 6, looking in the direction of the arrows. Fig. 35 8 is a detail view similar to Figs. 2 and 5, showing another modified arrangement embodying the principles of my invention. Fig. 9 is a detail sectional view on the line 9 9, Fig. 1, showing a modified arrangement wherein the frame end of the coupling-arm is adjustable 40 and embodying the principles of the invention. Fig. 10 is a broken detail view, in side elevation, of the construction shown in Fig. 9.

In the efficient operation of mowing-machines it is desirable and important to maintain accurate alinement between the cutter-bar and its operating-pitman. In use, through 45 the wear of joints and parts which support

the inner end of the finger-bar and the backward pressure exerted upon the finger-bar as the machine advances over the ground and 55 encounters the grain to be cut or other obstruction, a tendency is quickly developed in the finger-bar to sag backward, as indicated in dotted lines in Fig. 1, and it is evident that only slight wear of joints at the inner end of 60 the finger-bar will result in a magnified degree of backward sagging at the outer end of such bar. This backward sagging of the finger-bar is exceedingly objectionable and undesirable, for the reason that thereby the path 65 of reciprocation of the cutter-bar becomes deflected or changed out of accurate alinement with the pitman, through which reciprocations are imparted to the cutter-bar, and as a rapid reciprocation is imparted to the cutter-bar while the machine is in use such deflection of the path of reciprocation of the cutter from true and accurate alinement with the line of movement of the pitman through which the cutter-bar is reciprocated and which is 70 not affected by the rearward pressure upon the finger-bar or by wear in the parts which support the finger-bar develops friction and rapid wear and looseness of the cutter-bar, thus not only causing the machine to run 75 heavy, but rapidly wearing out the parts. Various expedients have been resorted to with a view to overcoming this difficulty; but so far as I am aware the difficulty has not heretofore been wholly overcome. For instance, it has been endeavored to overcome the objections noted by providing a construction wherein the coupling-arm has been shortened, thereby moving forward the yoke which supports the inner end of the finger-bar. This, 80 however, does not correct the difficulty, for the reason that in such case the bend in the line of movement of the cutter-bar with reference to the line of reciprocation of the operating-pitman, which latter remains fixed, 85 is not thereby removed. In other words, in such case the yoke which supports the inner end of the finger-bar is advanced, but the finger-bar itself is thereby merely moved parallel to itself, and therefore the alinement between the pitman and the finger-bar is not 90 restored. Noting the defects in the prior efforts to remove the difficulties mentioned and appreciating the practical importance of 95 100

avoiding such difficulties, I have conceived the idea of a construction wherein the yoke which carries the cutter-bar is mounted with its axis at an angle to the axis of the coupling-arm 5 and wherein by adjusting the relative position of one of these parts the angle of the finger-bar, and hence the path of reciprocation of the cutter, is changed relative to the longitudinal axis of the coupling-arm, and thus 10 removing any deflection from proper alignment between the cutter and its operating pitman. This idea may be carried out in many specifically different ways, and in the accompanying drawings I have shown various 15 practical constructions embodying the generic principles of the invention.

Referring to the drawings by reference-sign, A designates the frame of the mowing-machine, which may be of any suitable construction or type. 20

B is the finger-bar, C the coupling-arm, and D the yoke.

In the usual construction of mowing-machines of the type shown in the drawings the 25 coupling-arm is loosely hooked or pivoted at its inner end, as at E, to the machine-frame, and the outer end F of said arm is bent out of axial alignment with the arm. Upon this bent end F is suitably journaled the yoke D, 30 and the inner end of the finger-bar is suitably pivoted upon yoke D. A drag-bar G may be employed to connect the yoke to the tongue H of the machine. A fly-wheel J, suitably actuated in the usual or any suitable or 35 well-known manner, is provided with a crank or wrist pin K, to which is connected one end of pitman L, the other end of such pitman being connected to the cutter-bar and the latter mounted to reciprocate in a suitable guide in 40 the finger-bar.

The parts so far described may be of the usual or any well-known construction and arrangement, except as to the coupling-arm C, as will presently be pointed out.

45 It will be seen that pitman L reciprocates in a fixed line, and hence it is desirable and important in order to secure and maintain alignment between said pitman and the cutter-bar that any tendency of the finger-bar 50 in which the cutter-bar reciprocates to sag backwardly, as indicated in dotted lines in Fig. 1, be overcome in such manner as to move the outer end of the finger-bar forwardly without material relative movement of the inner 55 end of said bar with respect to the line in which pitman L reciprocates. In Figs. 1, 2, 3, and 4 is shown one form of arrangement whereby this result is secured, wherein I form the coupling-arm C in two parts, the frame 60 end part M being provided with the hook 10 to be received in the eyebolt E or other securing device in the usual manner. The inner end of the main part C of the coupling-arm is provided with a threaded longitudinal and 65 axial extension 11, arranged to be screwed into a threaded socket in the tail or end piece M. This construction permits of endwise adjust-

ment of the length of the coupling-arm in order to properly center the cutters 12 with reference to the fingers 13—that is, in order to 70 properly adjust the throw of pitman L, so that the cutters will operate in proper relation to the fingers.

By reason of the angular relation of the end F of the coupling-arm to the part C thereof it 75 will be readily seen that axial rotation of the part C of the coupling-arm will cause the angular end F thereof to change the direction 80 of its line of inclination with reference to the axis of the part C of the coupling-arm, and hence also will cause the finger-bar, and with it the cutter-bar, to correspondingly change 85 their line of inclination with reference to the axis of the coupling-arm, since the yoke D, which supports the inner end of the finger-bar, 90 is supported or journaled upon the angular end F. Thus it will be seen that by merely 95 rotarily adjusting the coupling-arm C axially any sagging or bending of the finger B, and hence of the cutter-bar, out of alignment with 100 the line of reciprocation of pitman L may be readily corrected. I have shown in Figs. 1, 2, 3, and 4 a simple and efficient arrangement for securing such axial adjustment, while maintaining when the adjustment is made 105 rigidity between the parts C and M of the coupling-arm. In this form of embodiment of the principle of my invention I provide the piece M with a flange 14 on the outer end thereof, with which contacts and coöperates a corresponding flange 15, suitably secured to the 110 part C of the coupling-arm. In the particular form shown, to which, however, the invention is not limited, flange 15 forms part of a sleeved casting 16, adapted to be mounted 115 on the adjacent end of the part C of the coupling-arm. A convenient manner of mounting this sleeve upon the part C of the coupling-arm is shown, wherein such part C is flattened at the end thereof, as shown at 17, and the sleeve 120 16 is driven tightly on such flattened end. A bolt 18 is arranged to pass through suitable perforations in said coöperating flanges 14 15, whereby said flanges may be secured together in adjusted position, one of said flanges, as 125 flange 15, being provided with a curved slot, as at 19, to permit of the relative rotary adjustment of the flanges 14 15. If desired and in order to more securely hold and maintain rigid connection between the two parts 130 C and M of the coupling-arm after the desired adjustment has been secured, one of the flanges, as 15, may be provided with serrations or teeth, as indicated at 20, adapted to receive a nib or lug 21, formed on the other 135 flange. By this construction, when the desired adjustment has been attained, the two parts of the coupling-arm are firmly and efficiently locked against relative movement. In order to effect an adjustment in case sagging 140 of the finger-bar is observed, the bolt 18 is loosened and the sleeve 16 is driven or moved endwise upon part C of the coupling-arm until the nib or lug 21 clears the teeth or serra-

tions 20, and then the part C of the coupling-arm is axially rotated the required amount to compensate for the sagging of the finger-bar, thus restoring the alinement between 5 the pitman L and the cutter-bar. When the desired adjustment is secured, the bolt 18 is again clamped up, thus firmly clamping the two parts C and M of the coupling-arm together.

10 Of course it will be readily understood that the adjustment secured by the axial rotation of the coupling-arm is wholly independent of the longitudinal adjustment of the coupling-arm for properly centering the cutters 12 with 15 respect to the fingers 13, and therefore, so far as the present invention is concerned, it is immaterial whether or not provision is made for longitudinal adjustment of arm C. While I have shown such longitudinal adjustment, 20 therefore, I desire it to be understood that the invention is not limited or restricted thereto.

In the modified form of construction shown in Fig. 5, embodying the same generic principle as above explained, instead of securing 25 the desired adjustment to correct a backward sagging of the finger-bar by axially rotating the coupling-arm the same result is secured through the medium of an eccentric sleeve 22. In the construction above described the yoke 30 D is shown mounted or journaled directly upon the angular end F of the coupling-arm.

In the modified construction shown in Fig. 5 I mount or journal the yoke D upon sleeve 22, which latter is journaled upon the angular extension F of the coupling-arm. The bore of this sleeve which receives the end F of the coupling-arm is slightly angular or inclined relative to the geometric axis of the said sleeve, as clearly shown. Therefore by 40 rocking or rotarily adjusting this sleeve upon the extension or end F of the coupling-arm it will be readily seen that the yoke D, and hence the finger-bar and cutter, is adjusted with respect to the axial line of the coupling- 45 arm C, and hence also with respect to the line of reciprocation of pitman L. Thus any disarrangement of the alinement of the pitman and the cutter-bar due to the sagging of the finger-bar may be corrected readily and easily 50 by rotarily adjusting sleeve 22. In order to secure the sleeve 22 and the yoke D together after the desired adjustment has been made, said parts are flanged, as at 23 24, and a bolt 25 passes therethrough, one of said flanges being provided with an elongated slot similar to slot 19 and for a similar purpose, as will be 55 apparent.

In some types of mowing-machines a thrust-bar or brace N is employed which is secured 60 to the coupling-arm at one end and to the framework of the machine at the other. In Fig. 8 I have shown an application of the principles of my invention to a mowing-machine of this type. In this form of the invention 65 the required adjustment is secured by axially rotating the coupling-arm C, as described with reference to Figs. 1, 2, 3, and 4. In this

case, however, the coupling-arm is secured in its axially-adjusted position by means of a sleeve 26, mounted rigidly on to rock with the 70 coupling-arm and provided with a flange 27, which co-operates with a flange 28, formed on the sleeve 29, which is secured to or forms part of the brace or thrust bar N and through which the coupling-arm loosely passes. A 75 bolt 30 serves to clamp said flanges together when the desired adjustment has been secured, one of said flanges being provided with an elongated slot similar to slot 19, as above explained, to permit of the desired relative 80 adjustment.

In that type of mowing-machine wherein the thrust or brace bar N is rigidly secured to the coupling-arm or forms a part thereof, as shown at N', Fig. 6, and wherein the yoke D 85 is mounted on the angular part F' of the coupling-arm C' in the same manner as above described the desired adjustment of the finger-bar to maintain alinement of the same with the path of reciprocation of the pitman in 90 accordance with the principles of my invention may be secured by vertically adjusting the frame end connection of the thrust or brace bar. In Figs. 6 and 7 I have shown a construction embodying my invention as applied to a mowing-machine of this type. In 95 this construction the frame end of the brace or thrust bar or extension N' is received in an eyebolt 31, suitably mounted in an arm 32 of the machine-frame and vertically adjustable therein in any suitable manner, as by means of the set-nuts 33 34.

In Figs. 9 and 10 I have shown an arrangement embodying the principles of my invention, wherein the desired adjustment of the 105 line of movement of the cutter-bar B relative to the line of action of its operating-pitman L is secured by the adjustment of the connection of the coupling-arm tail M in case of a divided coupling-arm, as shown in Fig. 8, 110 for instance, or end 10 in case of a solid coupling-arm, as in Fig. 5, upon the machine-frame. It is evident that by adjusting the tail or end connection of said coupling-arm upon the machine-frame—that is, by moving 115 or adjusting the eyebolt or other connection E in a fore-and-aft direction—the arm C will be rocked or swung about a fulcrum formed by the frame connection or support of the other end of the coupling-arm—as, for instance, the point of connection of the draw-bar G with yoke D (see Fig. 1) or the bracket N, (see Fig. 8,) in the latter case it being understood that a sufficient play in the bearings 120 in bracket N is provided to permit of slight 125 lateral rocking of the coupling-arm in such bearing.

In Figs. 9 and 10 I have shown the end 35 of the coupling-arm arranged to pass through a suitable opening or perforation in a block 130 36, which is mounted to slide in suitable guides, as at 37, in the frame A of the machine, and a set-screw 38, tapped through a lug 39, serves to effect the required adjust-

ment of block 36. Of course in this case, as well as in the construction shown in Fig. 7, the opening through which the end of the coupling-arm passes is sufficiently large to permit of the slight movement of such end therein during the adjustment.

Many other variations and changes embodying the principles of the invention would readily suggest themselves to persons skilled in the art and still fall within the spirit and scope of my invention. I do not desire, therefore, to be limited or restricted to the exact construction shown and described. It is also evident that the principles of my invention may be applied to different types and constructions of mowing-machines from that specifically illustrated in the drawings; but,

Having now set forth the object and nature of my invention and various embodiments of the principles thereof and having explained the construction, function, and mode of operation of such embodiments, what I claim as new and useful and of my own invention, and desire to secure by Letters Patent of the United

25 States, is—

1. In a mowing-machine, a main frame, a coupling-arm connected thereto, the end of said arm being deflected or bent into angular relation with respect to the axial line of said 30 arm, a cutter-bar supported upon said angularly-bent end, a pitman for reciprocating said cutter-bar, and means for rotarily adjusting said arm axially, as and for the purpose set forth.

2. In a mowing-machine, a main frame, a coupling-arm made in sections, one of said sections connected to the framework, a cutter-bar supported upon the other of said sections but out of axial alinement therewith, 40 and means for rotarily adjusting said section relative to the first-mentioned section, as and for the purpose set forth.

3. In a mowing-machine, a main frame, a coupling-arm having an end piece connected 45 to said framework, a flange formed on said end piece, a cutter-bar supported upon said coupling-arm but out of axial alinement therewith, and a flange carried by said coupling-arm, and means for connecting said flanges, 50 whereby said coupling-arm may be rotarily adjusted, as and for the purpose set forth.

4. In a mowing-machine, a main frame, a coupling-arm having an end piece connected to said frame, a flange carried by said end piece, a collar mounted on said coupling-arm 55 and provided with a coöperating flange, a bolt for connecting said flanges, whereby said coupling-arm may be rotarily adjusted relative to said end piece, and a cutter-bar supported upon said coupling-arm out of axial alinement therewith, as and for the purpose set forth.

5. In a mowing-machine, a main frame, a coupling-arm having an end piece connected to said frame, a flange carried by said end 65 piece, a collar mounted on the adjacent end of said coupling-arm for endwise movement thereon, said collar provided with a coöperating flange, one of said flanges provided with teeth or serrations and the other with an engaging lug, a bolt for coupling said flanges, one of said flanges being provided with an elongated slot through which said bolt passes, whereby said coupling-arm may be rotarily adjusted axially, and a cutter-bar supported 75 upon said coupling-arm but out of axial alinement therewith, as and for the purpose set forth.

6. In a mowing-machine, a coupling-arm, a cutter-bar supported upon said arm in eccentric relation to the axis thereof, a pitman for actuating said cutter-bar, and means for adjusting the position of the coupling-arm whereby through such eccentric relation alinement between the pitman and the cutter-bar is restored, as and for the purpose set forth.

7. In a mowing-machine, a cutter-bar, a coupling-arm upon which said bar is mounted, the line of movement of said cutter-bar being normally inclined relative to the axial line of 90 said arm, a pitman for reciprocating said cutter-bar, and means for axially adjusting said coupling-arm, whereby the backward sag of the outer end of the cutter-bar is compensated for, as and for the purpose set forth.

In witness whereof I have hereunto set my hand, this 2d day of May, 1898, in the presence of the subscribing witnesses.

MAURICE KANE.
